(57) **CLAIM**

The ornamental design for a night light, as shown and described.

DESCRIPTION

FIG. 1 is a first perspective view of a night light showing my new design;
FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in. FIG. 2.

The broken lines shown in the drawings depict portions of the night light that form no part of the claimed design. The broken lines of alternating length in the drawings are for the purpose of illustrating the boundaries of the enlarged fragment shown in FIGS. 2 and 9.

1 Claim, 9 Drawing Sheets
